UNITED STATES PATENT OFFICE.

JAMES A. LONG, OF KALISPELL, MONTANA.

BEET-THINNER.

No. 857,815.

Specification of Letters Patent.

Patented June 25, 1907.

Application filed March 4, 1907. Serial No. 360,372.

To all whom it may concern:

Be it known that I, JAMES A. LONG, a citizen of the United States, residing at Kalispell, in the county of Flathead, State of Montana, have invented certain new and useful Improvements in Beet-Thinners; and I do hereby declare the following to be a full, clear, and exact description of the invention, such as will enable others skilled in the art to which it appertains to make and use the same.

This invention relates to beet thinners and more particularly to that class employing a plurality of rotary blades.

15 The primary object of my invention is to provide means for regulating the height of the thinning blades and means for raising and lowering these blades clear of the ground while turning the machine to start a new row 20 and in order to carry out the first mentioned feature or object of my device, I employ a wheel standard, carrying a wheel and adjustably connected with this standard is a second standard having a yoke in which is rotatably 25 mounted with sets of thinning blades and the second mentioned object is accomplished by means of levers which may be operated to raise or lower both the gage wheel and the sets of thinning blades.

30 In the accompanying drawings, Figure 1 is a side elevation of a beet thinning machine constructed in accordance with my invention, Fig. 2 is a top plan view thereof, Fig. 3 is a rear elevation, Fig. 4 is a detail vertical 35 longitudinal sectional view therethrough, Fig. 5 is a detail perspective view of one of the gage wheel beams, the gage wheel, the related beam for the thinning devices, and the said thinning devices, and, Fig. 6 is a detail 40 perspective view of one of the thinning blades, and, Fig. 7 is an edge of one of the sprocket gears.

Referring more specifically to the drawings the machine is shown as comprising an 45 axle 10 which is journaled for rotation upon the underside of a tongue 11 and which carries at each of its ends a ground wheel 12. Rotatably journaled in a suitable bearing 13 upon the under side of the tongue 11 and a 50 short distance below the plane occupied by the axle 10 is a shaft 14 and this shaft is braced adjacent its ends by means of arms 15 which are connected at their ends loosely with the axle 10 and the shaft 14.

55 A plurality of gage wheel standards 16 having yoked forward ends 17 are loosely

connected at their said ends with the shaft 14 and are held against lateral movement upon the shaft by means of suitable collars 18. These standards 16 extend downwardly and rearwardly and have their rear end portions turned directly downwardly as at 19 and again forms a yoke 20 in which is rotatably journaled a gage wheel 21. Adjacent its down turned portion 19, each of the standards 16 is provided with an opening 22 and a series of openings 23 are formed through the down turned portion of each standard. A bolt 24 is engaged through the opening 22 in each of the standards 16 and also through the extreme forward end of a standard 25 thereby pivotally connecting the said standard with an standards 16 and engaged through the opening 26 in the standard 25 and interchangeably through the openings 27 in the standards 16 is a bolt 28 this connection between the two beams serving as a means whereby the standards 16 and 25 may be relatively positioned. The rear end of each of the standards 25 is turned downwardly as at 28 and is in the form of a yoke, there being journaled in the arms of the yoke a shaft 29 carrying arms 30 to the outer ends of which are bolted or otherwise secured blades 31 which have their end edges adjacent their forward or cutting edges, tapered as at 32, the cutting edge of each blade being indicated by the numeral 33. These blades of course are so connected with the arms 30 that as the shaft 29 is rotated, the blades will 35 chop the plants close to the ground.

Upon the axle 10 is arranged a sprocket gear 34 which is provided upon each of the sides with a flange 35 which extends beyond its periphery and upon opposite ends of the 40 chain which is engaged over the sprocket and which is indicated by the numeral 36, it being understood that these flanges prevent the chain leaving the gear. This chain is also engaged over a sprocket gear 37 of like construction which is carried by the shaft 14 at one end thereof and serves as a means whereby the shaft will be rotated during the progress of the machine. Besides this gear 37 upon the shaft 14 there is arranged upon the 45 shaft a number of other gears of like construction which are indicated by the numeral 38 and are equal in number to the number of standards 16 and in fact these last mentioned sprocket gears are located one 50 upon one side of each yoke portion 17 of the standard 16 and are geared by means of a

sprocket chain 39 and gear 40 with the corresponding shaft 29.

Loosely engaged upon the axle 10 between each wheel 12 and the tongue 11 is a sleeve shaft 41 and upon each sleeve shaft is formed a number of arms 42 equal to one half the number of standards 16 there being a chain 43 connected with each arm at its upper end and at its lower end with the respective one of the standards just mentioned. Formed upon each sleeve shaft at its inner end and extending substantially in a diametrically opposite direction to the arms 42 is an arm 44 to which is connected one end of a rod 45 which leads to and is pivotally connected to the lower end of a lever 46 arranged upon one side of the tongue, it being understood of course that there are two such levers, one being connected with each sleeve shaft and arranged upon the tongue is a pair of segmental racks 47 for the co-operation therewith of hand operated pawls 48. It will be readily understood that by rocking either one of these levers or both of them, the standards 16 to one side or to both sides respectively of the machine may be raised or allowed to lower.

What is claimed is—

1. A machine of the class described comprising an axle mounted for rotation, a shaft driven from the axle, gage wheel standards loosely connected with the shaft, gage wheels journaled upon the standards, standards adjustably connected with the gage wheel

standards, a shaft journaled in the last mentioned standards, cutting elements carried by the shafts, gear connections between the driven shaft and the shaft carrying the cutting elements, sleeve shafts arranged upon the axle for turning movement independent thereof, connections between the sleeve shafts and the gage wheel standards, and means for rocking the sleeve shaft for raising and lowering the standards.

2. A machine of the class described comprising an axle mounted for rotation, a shaft driven from the axle, gage wheel standards loosely connected with the shaft, gage wheels journaled upon the standards, standards adjustably connected with the gage wheel standards, a shaft journaled in the last mentioned standards, cutting elements carried by the shafts, gear connections between the driven shaft and the shaft carrying the cutting elements, sleeve shafts arranged upon the axle for turning movement independently thereof, arms carried by the sleeve shafts, connections between the arms and the gage wheel standards, and means for rocking the sleeve shafts to raise and lower the standards.

In testimony whereof, I affix my signature, in presence of two witnesses.

JAMES A. LONG.
